UNITED STATES PATENT OFFICE

172,841

PASTRY BOARD

Hyman B. Peck, Rochester, N. Y.

Application February 14, 1952, Serial No. 18,517

Term of patent 14 years

(Cl. D44—1)

To all whom it may concern:

Be it known that I, Hyman B. Peck, a citizen of the United States of America and resident of Rochester, in the county of Monroe and State of New York, have invented a new, original, and ornamental Design for a Pastry Board, of which the following is a specification, reference being had to the accompanying drawings, forming part hereof.

Fig. 1 is a top plan view of a pastry board, showing my new design;

Fig. 2 is a side elevational view of the front edge thereof; and

Fig. 3 is a sectional view taken substantially along line 3—3 of Fig. 1.

The stippling or shading in Fig. 1 is intended to show colored stripes on the surface of the board, along opposite sides of each of the grooves in the

board, the stripes associated with each circular groove and its connected tangential guide groove being of a color contrasting with that of the stripes associated with other grooves.

I claim:

The ornamental design for a pastry board, substantially as shown and described.
